UNITED STATES PATENT OFFICE.

FRANK GOTTESMAN, OF NEW YORK, N. Y.

TABLE ATTACHMENT FOR BEDS.

1,137,753.

Specification of Letters Patent.

Patented May 4, 1915.

Application filed April 3, 1914. Serial No. 829,222.

To all whom it may concern:

Be it known that I, FRANK GOTTESMAN, a subject of the Emperor of Germany, residing at New York, in the county of New York and State of New York, have invented certain new and useful Improvements in Table Attachments for Beds, of which the following is a specification.

This invention relates to certain new and useful improvements in table attachments for beds.

The primary object of the device is the provision of a plurality of table members relatively adjustable for employment by the occupant of the bed as for eating and reading purposes.

A further object is to provide two adjustable table members pivoted to opposite sides of a bed and readily foldable when not desired for use, the table members having a pivotal connection therebetween.

A still further object is to provide tables pivoted together and adjustably pivoted to opposite brackets carried by a bed, which brackets are adjustable in position and foldable upon the side rails of the bed.

With these general objects in view and others that will appear as the nature of the invention is better understood, the same consists in the novel combination and arrangement of parts hereinafter fully described, illustrated in the accompanying drawings, and pointed out in the appended claim.

In the drawings forming a part of this application and in which like designating characters refer to corresponding parts throughout the several views:—Figure 1 is a perspective view of a bed with the improved table operatively positioned thereon.

Fig. 2 is a transverse vertical sectional view taken through the bed and the device as positioned in Fig. 1, and Fig. 3 is a side view of the device, partly in section mounted upon a portion of a side rail and shown in dotted lines in its tilted position.

Referring more in detail to the drawings, the bed 10 is shown with its opposite side rails 11 provided with oppositely-arranged brackets 12 pivoted to the outer sides of said rails by means of the bolts 13 and adapted to be secured in adjusted tilted positions by means of winged nuts 14 screw-threaded upon said bolts.

The brackets are provided with outwardly-

extending bosses 15, adjacent their upper ends, each of which is provided with a rod 16 mounted therein and secured in its adjusted position by means of a winged screw 17 while the tables 18 are mounted upon the rods 16 by means of straps 19 screws 20 being screw-threaded through these straps and engage the carrying rod for retaining the table top in its desired inclined position.

One of the rods 16 is provided with the reduced extension 21 and adapted for reception within a socket 22 in the end of the other rod and whereby the two rods are positioned in alinement while the tables 18 may be individually secured at different inclinations.

From the above detailed description, it is thought that the complete operation of the device will be at once apparent in that with the tables assembled extending over the bed, the entire structure may be tilted as shown in dotted lines in Fig. 3 and then secured by means of the winged nuts 14 engaging the side brackets 12. When desired to disassemble the device, the screws 17 and 20 are released, and the rods 16 slidably removed from the tables and brackets while the brackets may be folded downwardly in either direction upon the outer sides of the bed rails and with the notches 23 of the brackets seating over the pins 24 outwardly-extending from the side rails.

While the forms of the invention herein shown and described are what are believed to be preferable embodiments thereof, it is nevertheless to be understood that various forms and modifications may be had without departing from the spirit and scope of the invention as claimed.

What I claim as new and desire to secure by Letters Patent of the United States is:

A device of the class described comprising in combination with the side rails of a bed, outwardly-projecting bolts carried by said rails oppositely-arranged brackets mounted upon said bolts, winged lock nuts carried by said bolts and adapted to engage said brackets in their adjusted positions, said brackets provided with opposite open slots and with perforated bosses at their upper ends, outwardly-extending pins upon said side rails upon opposite sides of said bolts adapted to be received in said slots upon a folding of said brackets, rods adjustably mounted in

said bosses in alinement with each other and having a pin and socket engagement at their inner contacting ends, tables upon said rods, straps upon the under sides of said tables 5 and surrounding said rods, and screws extending through said straps and adjustably engaging said rods.

In testimony whereof I affix my signature in presence of two witnesses.

FRANK GOTTESMAN.

Witnesses:

JOSEPH P. ELMAS,
STANISLAU OLDOCMOV CZUK.
